[57] CLAIM

The ornamental design for an air purifying unit for removing smoke from the interior of a car, as shown.

DESCRIPTION

FIG. 1 is a top, front and right side perspective view of an air purifying unit for removing smoke from the interior of a car showing my new design;

FIG. 2 is an enlarged front elevation view thereof;

FIG. 3 is an enlarged rear elevation view thereof;

FIG. 4 is an enlarged left side elevation view thereof;

FIG. 5 is an enlarged right side elevation view thereof;

FIG. 6 is an enlarged top plan view thereof; and,

FIG. 7 is an enlarged bottom plan view thereof.

FIG. 1

FIG. 4

FIG. 5

FIG. 2

FIG. 3

FIG. 6

FIG. 7
